LOW FOAMING DETERGENT FOR AUTOMATIC DISHWASHING MACHINE

Richard A. Grifo, Easton, Pa., and Raymond L. Mayhew, Phillipsburg, N.J., assignors to General Aniline & Film Corporation, New York, N.Y., a corporation of Delaware

No Drawing. Filed Jan. 10, 1958, Ser. No. 708,066
2 Claims. (Cl. 252—135)

The invention here presented is a new and useful low-foaming, low-sudsing detergent, especially adapted for automatic dishwashing machines, in the form of a substituted phenol containing a chain of a critical number of ethylene oxide molecules.

Various of the automatic dishwashing machines impose rather severe limitations upon the detergent which can be used therein, and low-foam detergents are required in order to avoid interference with the mechanical operation of the washer and to permit of clean rinsing with the facilities available in the machine. To the present, none of the available detergents are found to be fully satisfactory. One of the better dishwashing machines uses a rotating arm carrying a jet on the end thereof, through which detergent solution is forced in the form of a spray or stream which serves the dual purpose of applying detergent solution to the dishes and of rotating the arm so that the spray travels under the dishes and gives each one a vigorous application of detergent solution by the utilization of a jet or spray under considerable pressure. However, it has not been found mechanically convenient to drive the spray by power, because of the danger of breaking any silver or dish which may drop through the tray into the path of the jet, and it is accordingly essential that the jet shall be flexibly driven so that it will stop, if an impediment is in the path, without breaking dishes or bending silver.

Accordingly, a swinging arm is lightly journaled in the bottom of the washer, below the dishes, and the reaction pressure in the jet is utilized to spin the journal arm and ensure coverage of all of the dish surfaces. In addition, it is necessary that a minimum of water spots be left on glassware washed in the machine, which means that the detergent solution must be of such character that it can be very easily rinsed off from the dishes. In view of this situation, a high-foam detergent is contraindicated, since a thick suds may stop the swinging arm entirely, and a thick suds is difficult to rinse off from glasses and dishes.

According to the present invention, it is now found that an alkyl substituted phenol, having from 8 to 12 carbon atoms in the alkyl chain, and a polyoxyethylene chain containing, on the average, an amount of ethylene oxide within the range between 40% to 47% of the ethylene oxide, is highly effective since it yields a very low suds, too low in quantity to interfere with the rotation of the jet arm and low enough to be easily rinsed off of both glassware and dishes by a jet of clear water through the same swinging arm and spray head; and at the same time has a powerful detergent action, strong enough to ensure a complete freeing of all traces of grease and other adherent matter from dishes and glassware.

It will be observed that a maximum detergent power is called for, together with a minimum of suds, and it is found that this requirement sets a sharply critical series of limitations upon the composition of the detergent. Thus the base is phenol containing an aliphatic substituent which is predominantly nine carbon atoms long, and averages, in analysis, close to nine atoms, minor quantities of other phenols being permissible. With this there are then combined ethylene oxide molecules to form a polyoxyethylene chain, which, again, is critical in length and preferably contains a major proportion of four ethylene oxide molecules, although minor proportions of three

2

molecule substituents and minor proportions of five molecule substituents are allowable as long as the average lies close to the four molecule constitution.

As this material is readily water dispersible and in an amount equal to 0.25% of the amount of water present, it gives an excellent detergent action, with no interference with the spray arm rotation, and is easily rinsed off from glassware and china to leave a minimum of water spots thereon.

10 The test procedure is as follows:

The foaming properties of these products were tested with the use of the Kitchen Aid dishwashing machine. This machine consists of a rotating arm through which the detergent solution is pumped, the revolutions per minute of the arm which can be measured easily is dependent on the amount of foam produced from the solution, so that an excess of foam will actually stop the machine. Consequently, a decrease in r.p.m. signifies an increase in foam.

20 The dishwashing or water spotting performance of the products was tested by washing glass tumblers in the above-mentioned dishwasher together with the product to be tested and a greasy soil consisting of oleomargarine and Starlac (powdered skim milk). The glass tumblers are

25 rated according to the number of dried water spots remaining on the tumblers. In order to compare the various products tested on an equal basis, the data reported relative to nonylphenol + 4 moles ethylene oxide which is made equal to 100. Any value below 100 is better for 30 water spotting.

Thus the composition of the invention consists of a benzene ring having substituted thereinto an aliphatic chain of approximately 9 carbon atoms, and a chain of approximately 4 ethylene oxide units which is found to be an excellent detergent; to produce a minimum of foam and to rinse off of glass or china surfaces with a minimum of water spots. Other objects and details of the invention will be apparent from the following description:

35 The first component of the substance of the invention is a nonylphenol, which is available on the open market or may be prepared by alkylation of phenol. For this purpose the phenol containing the alkyl substituent is treated with a suitable amount of ethylene oxide, as is well shown in United States Patent No. 2,213,477, to yield the 40 type of polyoxyethylene glycol phenol ether therein disclosed. The resulting compound of nonylphenol with 4 moles of ethylene oxide per mole of nonylphenol is the primary component of the invention. It may be noted, as above pointed out, that none of these reactions yield 45 single pure substances, and accordingly the amount stated is present in a major proportion, but nearly always is accompanied by minor proportions of the higher and lower ratio compounds; and as long as the desired compound is present in major proportion, and analysis 50 shows an average number of ethylene oxide molecules, the exact amount and exact size of substituents is of minor or negligible consequence. This compound is the base of 55 the composition of the invention.

60 This compound of nonylphenol and ethylene oxide, in the proportions above indicated, is an excellent detergent; but it is found, further, that its detergent power can be substantially increased by the procedure of "building" the detergent, by which procedure the liquid nonylphenol 65 ethylene oxide compound can be converted from a viscous liquid to a nearly solid granular compound if desired. This procedure involves the addition to the nonylphenol ethylene oxide compound of appropriate auxiliary substances, such as sodium metasilicate, trisodium phosphate, sodium tripolyphosphate, sodium pyrophosphate, sodium hexametaphosphate, and the various other polyphos-

phates, as well as various other substances which are well known in the art.

EXAMPLES

Fourteen tests were run on various proportions and sizes of the respective substituents on the phenol grouping, yielding 14 separate examples. The results are shown in the following table, in which the composition of the detergent is indicated in the first column, the percentage of ethylene oxide present is indicated in the second column, the revolutions per minute of the agitator in the washer is shown. The last column shows the relative intensity of water spotting, all as above outlined.

Mechanical dishwashing evaluation

[Tapwater temp. at 140° F. Product conc. 0.25%]

Surfactant	Percent EtO	Foam, r.p.m. of Agitator	Water Spotting Relative to Nonylphenol +4 Moles Ethylene Oxide Equal to 100
1. Nonylphenol+1½ E.O.	23	-----	155
2. Nonylphenol+3 E.O.	38	-----	140
3. Nonylphenol+4 E.O.	45	80	100
4. Nonylphenol+5 E.O.	50	25	105
5. Nonylphenol+6 E.O.	55	20	105
6. Nonylphenol+9 E.O.	64	40	90
7. Nonylphenol+15 E.O.	75	0	-----
8. Phenol+2 E.O.	58	-----	165
9. Pentylphenol+2 E.O.	35	-----	140
10. Diisobutylphenol+4 E.O.	46	85	90
11. Nonylphenol+4 E.O.	45	80	100
12. Dodecylphenol+6 E.O.	50	-----	160
13. Dinonylphenol+3.5 E.O.	30	-----	190
14. Dinonylphenol+7 E.O.	47	-----	175

The surfactant in each instance was "built" by mixing 5% of the indicated surfactant, or detergent, with 95% of a builder, consisting of one part sodium metasilicate with 3 parts of sodium tripolyphosphate.

Similar tests were applied to detergents available on the market, the exact composition of each being unknown other than the fact that each lacked any ethylene oxide substituent. The results are shown in the following table:

Mechanical dishwashing evaluation

[Tapwater temp. at 140° F. Product conc. 0.25%]

Surfactant	Percent EtO	Foam, r.p.m. of Agitator	Water Spotting Relative to Nonylphenol +4 Moles Ethylene Oxide Equal to 100
Triton CF-10	0	75	100
Chat (as is)	0	50	105
Calgonite (as is)	0	80	220
Cascade (as is)	0	20	-----
Builders alone	0	90	170

It will be noted in the above tables that only those compounds containing 4 moles of ethylene oxide per mole of nonylphenol gave a sufficiently low foam to permit of ready rotation of the jet arm, and that of the 14 compositions several produced so much foam or suds as to stop the jet from rotating. Similarly, only those compounds containing 4 moles of ethylene oxide per mole of substituted phenol gave a reasonably good freedom from water spotting.

Accordingly, it will be observed that for a swinging-

arm dishwasher, which is known to require very carefully adapted detergent, substituted phenols, containing 4 molecules of ethylene oxide, were uniformly critical in proportion and were the only ones which produced detergent which did not interfere with the rotation of the jet arm, and at the same time gave a good freedom from water spots upon rinsing.

Thus the invention consists of a low-foam detergent in the form of a benzene ring having thereon an aliphatic substituent having an average chain length of 9 carbon atoms, and a second substituent in the form of a condensation product of ethylene oxide containing an average of 4 ethylene oxide molecules per molecule of nonylphenol; the mixture being conveniently combined with suitable builders for use in a swinging-arm dishwasher machine.

While there are above disclosed but a limited number of embodiments of the invention, it is possible to produce still other embodiments without departing from the inventive concept herein disclosed, and it is therefore desired that only such limitations be imposed upon the appended claims as are stated therein or required by the prior art.

The invention claimed is:

1. A low-foam detergent composition for use in a swinging-arm dishwasher consisting essentially of a phenol having therein an aliphatic substituent with an average number of 9 carbon atoms per chain, and a second substituent comprising condensed ethylene oxide in an average number of 4 molecules per molecule of phenol together with builders consisting essentially of a mixture of sodium metasilicate and sodium tripolyphosphate in the proportion of one part of metasilicate to three parts of tripolyphosphate, the builders being present in the proportion of 95 parts of builder mixture to 5 parts of nonylphenol ethylene oxide.

2. A low-foam detergent composition for use in a swinging-arm dishwasher consisting essentially of a phenol having therein an aliphatic substituent with an average number of 9 carbon atoms per chain, and a second substituent comprising condensed ethylene oxide in an average number of 4 molecules per molecule of phenol together with builders consisting essentially of a mixture of sodium metasilicate and sodium tripolyphosphate in the proportion of one part of metasilicate to three parts of tripolyphosphate, the builders being present in the proportion of 95 parts of builder mixture to 5 parts of nonylphenol ethylene oxide, together with water in an amount equal to 400 times, by weight, of the amount of nonylphenol and builders together.
